AUTOMOBILE FOOT REST

John T. Clark, 400 Leland Place, Lansing, Mich. 48917

Filed July 20, 1967, Ser. No. 7,902

Term of patent 14 years

(Cl. D14—6)

FIGURE 1 is a perspective view of an automobile foot rest showing my new design;

FIGURE 2 is a side elevational view thereof;

FIGURE 3 is a front elevational view thereof;

FIGURE 4 is a sectional view thereof taken on line IV-IV of FIGURE 2; and

FIGURE 5 is a sectional view thereof taken on line V-V of FIGURE 2.

The portion shown in broken lines is included for illustrative purposes only.

I claim:

The ornamental design for an automobile foot rest, as shown and described.
